CLAIM

I claim the ornamental design for the grill of a feeder assembly, as shown and described.

DESCRIPTION

FIG. 1 is a perspective view of the grill of a feeder assembly of our design;

FIG. 2 is a top plan view of the grill of a feeder assembly of our design;

FIG. 3 is an enlarged front view of the grill of a feeder assembly of our design;

FIG. 4 is an enlarged rear of the grill of a feeder assembly of our design;

FIG. 5 is an enlarged right side view of the grill of a feeder assembly of our design; and,

FIG. 6 is an enlarged left side view of the grill of a feeder assembly of our design.
